UNITED STATES PATENT OFFICE.

OSCAR C. KAVLE, OF SYRACUSE, NEW YORK, ASSIGNOR TO WALLACE M. WEEKS AND JOHN A. PEASE, OF SKANEATELES, NEW YORK.

APPARATUS FOR SEALING BOTTLE CLOSURES.

Application filed February 25, 1926. Serial No. 90,711.

This invention relates to a method of and apparatus for adhesively sealing the caps or closures of milk bottles, and the like, and has for its object, to provide a novel and simple method of applying the adhesive, by which certain styles of closures may be temporarily secured to the beaded mouths of the bottles, for preventing accidental displacement and unauthorized removal of the closure, as well as for excluding dirt and germs from the bottle mouth. And a further object is to provide a novel and simple apparatus, by means of which the method may be conveniently and effectively carried out, the said apparatus being especially designed for effecting the positive and uniform sealing of the closures by a relatively small amount of the adhesive.

The various features and parts of the invention will be understood from the detailed description which follows, and by reference to the accompanying drawing, in which—

Figure 1 is a top plan view of the vat which contains the adhesive; showing the mechanism that supports the bottle while the closure is being immersed in the adhesive. Fig. 2 is a central vertical section, taken on line 2—2 of Fig. 1, showing the bottle in the sealing position, and the closure partially submerged in the liquid adhesive. Fig. 3 is a broken sectional view; showing the tension controlled parts of the apparatus extended. Fig. 4 is a top plan view of the bottle neck; showing adjacent portions of the closure and bead coated with the adhesive, and Fig. 5 is a broken elevational view of the same.

It is to be expressly understood that the drawing is merely illustrative of the object of the invention and accordingly shows one manner in which the invention may be practiced.

In the drawing, 2 represents a vat or tray, shown partially filled with an adhesive α , which according to the present showing is preferably melted paraffin, the top of the vat being normally open. Any suitable heat-producing means (not shown) may be employed for maintaining the paraffin in the melted state. Within the vat 2, is disposed the mechanism by which a bottle, as 3, having its mouth closed by a cap or closure 4, may be supported during the sealing operation. The immersing apparatus comprises a base 5, having a cylindrical body 5', which

is supported above and clear of the bottom of the vat, by means of legs 5^a. The body 5' is bored out axially, as at 5^b, to receive a reciprocatable plunger or pedestal 6, upon whose top end is rigidly mounted a cup-shaped part 6' that directly supports the bottle 3 during the sealing operation. The plunger 6 preferably supports a cushion spring 7, whose tension tends to normally hold the guard 6' extended and partially submerged in the adhesive α , as shown in Fig. 3. The plunger 6 preferably extends a short distance below the body 5 and its lower end is perforated to receive a pin 5^c, which prevents the plunger from being withdrawn from the body, and also tends to limit the vertical movements of the plunger and guard, during the sealing operations. The immersing apparatus is usually assembled, and the reciprocatable parts are adjusted, before the device is disposed in the vat 2. The vat is then filled with the adhesive α , the level of which is preferably so regulated that, when the bottle 3 is applied to the guard 6', and the said parts are depressed for sealing the cap 4, their downward movement is arrested by the lower end of the plunger contacting with the bottom 2' of the vat as shown in Fig. 2. The depth of the liquid α may be gauged by any suitable level gauge, as for example a groove or mark, as indicated on the inner walls of the vat at 2^a (see Figs. 2 and 3). As each bottle is immersed in the adhesive and removed, the spring 7 lifts the plunger and guard to the idle position shown in Fig. 3. Ordinarily the immersing parts are normally submerged to the extent shown in Fig. 3, wherein the level of the adhesive coincides substantially with the plane of the bottom of the guard 6'. When the apparatus is in the latter position the plunger 6 is spaced from the bottom of the vat 2, a distance corresponding to the downward or sealing stroke of the pedestal and related parts, and is calculated to permit the dipping of the bead of the bottle mouth substantially to the extent shown by the oblique shading in Figs. 4 and 5, in which the paraffin α is applied in a relatively narrow annular band upon the peripheral margin of the closure 4, and a similar band of the adhesive is shown applied to the bead 3^a, of the bottle. By this method, owing to the searching nature of the hot paraffin, the latter penetrates the joint between the cap 4

and the bead 3^a, and when cooled, effects a substantially air tight seal of the said parts. I prefer to use melted paraffin for the adhesive agent, for the reason that while it effects a perfect sealing of the joint between the cap and bead, and holds the said parts securely while the bottle is being handled, at the filling station, along the delivery route, as well as while awaiting use of the contents of the bottle, yet the cap 4 may be readily and quickly removed by the application of a slight prying force, as by the use of the fingers, or a table knife, for breaking the seal. The paraffin in vat 2 is preferably maintained at a high temperature, and when applied to the bottle, acts as a sterilizer, and being tasteless and odorless, and devoid of acids or other disagreeable or dangerous qualities, is not liable to contaminate or foul the contents of the bottle when the latter is poured over the portion of the bead 3^a that is still coated with the adhesive. Paraffin is comparatively cheap, and when applied in a relatively narrow band, as shown, enables me to effect a satisfactory seal of the bottle mouths at slight expense. Furthermore, by sealing the bottle caps as herein shown and described, unauthorized breaking of the seal for tampering with or extracting the contents of the bottle may be instantly detected by the consumer at a glance.

The cap 4 is preferably made of pliant somewhat absorbent fibrous stock, to which the sealing agent readily adheres, and which insures the effective sealing, as explained. By the method and means herein shown and described, the sealing of the bottles may be effected at the rate of one bottle per second. When the relatively narrow annular lip 6^a of the guard is properly seated against the cap 4, as shown in Fig. 2, the weight of the bottle 3 supplemented by the pressure exerted by the operator during the immersing operation, ordinarily prevents the paraffin from escaping into the cavity of the guard. In case any of the adhesive enters the said cavity, the liquid may drain off by means of a small opening 6^c, as shown in Figs. 1 and 2. In practice, the lip 6^a of the guard is arranged to expose only the relatively narrow annular portion, as 4^a of the cap, to the heated paraffin, and in order to effect the substantial registry of the bottle mouth with the guard 6', the latter is provided with upwardly extending flexible guides 6^b, which are preferably spaced equidistantly around the flange 6^a, as shown in Figs. 1, 2 and 3. These guards, in addition to effecting the axial alignment of the bottle and guard tend to prevent the displacement of the bottle laterally during the sealing operation.

The temperature of the bottles and caps is usually relatively low as compared with the temperature of the adhesive α , and the ad-

hesive therefore readily and quickly chills and sets, which greatly facilitates the rapid sealing and handling of the bottled products.

Having thus described my invention, what I claim is—

1. In an apparatus for supporting a bottle during the sealing of a closure that overlies the bottle mouth, the combination with a vat adapted to be partially filled with a heated liquid adhesive, of an immersing mechanism comprising a base supported by the bottom of the vat, a vertically reciprocatable plunger supported by the base, the top end of said plunger comprising a cup adapted to receive the covered mouth of the bottle when the latter is inverted, tension means for normally holding said cup above the level of adhesive, said cup and said plunger adapted to be depressed by the weight of the bottle, for immersing portions of the head of the bottle mouth and the periphery of the closure in the adhesive, and means for gauging the submerging stroke of the said plunger and cup. 70 75 80

2. In a device for immersing the mouth of a bottle closed by a cap the combination with a vat adapted to be partially filled with a heated liquid adhesive, a base having a tubular body supported by legs that rest upon the bottom of the vat, a plunger reciprocatable in said tubular body, the top end of said plunger being formed with a cup-shaped guard, the annular lip of said guard adapted to engage the bottle closure near its peripheral margin, tension means for normally holding the lip of said guard above the level of said adhesive, said plunger adapted to be depressed a measured distance for effecting the immersion of the exposed margin of the closure and the portion of the bead of the bottle mouth adjacent the closure, and flexible guides spaced around said guard for effecting the registry of the bottle mouth with the lip of said guard. 90 95 100 105 110

3. A device for sealing bottle closures, comprising a vat adapted to be filled with a heated liquid adhesive, an immersing mechanism disposed in said vat and partially submerged in said adhesive, said mechanism comprising a base that rests upon the bottom of the vat, a pedestal supported by and reciprocatable in a vertical plane in said base, a cup-shaped guard mounted on the top end of said pedestal having an annular lip of smaller diameter than the closure adapted when an inverted bottle is applied to said guard, to engage the closure and to expose the peripheral margin thereof, a spring adapted to normally hold said lip above the level of the liquid adhesive, said pedestal and guard adapted to be depressed for immersing the exposed margin of the closure and the adjacent portion of the bead of the bottle mouth in the hot adhesive, and means for gauging the vertical movement of the 115 120 125 130

pedestal and bottle for applying a relatively narrow band-like coating of adhesive to said closure and bead.

4. In an apparatus for sealing bottle closures, container means for holding liquid adhesive, means in the container means to engage the closure and cover the part of the closure which registers with the mouth of the bottle, and means for mounting one of said two first named means for movement relative to the other whereby to cause the bottle and its closure to engage with the adhesive below the surface of the latter so as to apply adhesive to the bottle and its closure.
- 15 5. In an apparatus for sealing bottle closures, container means for holding liquid adhesive, means in the container to engage the closure and cover the part of the closure which registers with the mouth of the bottle, means to mount the covering means for movement above and below the surface of the

adhesive, and means to normally dispose the covering means above the surface of the adhesive.

6. In an apparatus for sealing bottle closures, a liquid adhesive container, a spring pressed plunger in the container, means on the plunger to engage the closure and cover that part of the closure which registers with the mouth of the bottle, and means to mount the plunger in the container whereby to normally dispose the covering means above the level of the adhesive and upon downward movement of the plunger to cause the covering means to move below the level of the adhesive, said plunger being of a length to engage the bottom of the container upon downward movement thereof thereby to pre-determine the degree of submergence of the covering means in the adhesive.

In testimony whereof I affix my signature.
OSCAR C. KAVLE.
